TICKER TAPE CONTROLLING MEANS

James W. Decker, New York, N. Y.

Application January 25, 1928, Serial No. 249,384
Renewed May 29, 1934

6 Claims. (Cl. 88—24)

This invention relates to news projecting machines in general and more especially to improvements conducive to the production of a compact machine.

Among the objects of the present invention it is aimed to provide an improved projecting machine cooperating with a ticker or the like printing mechanism and a jump dissipating mechanism in which the printed matter extending from the printing location to the projecting location is reduced to a minimum so that the interval of time between printing and projecting a given character is reduced to a minimum, and whereby when the printer comes to rest the resulting delay in projecting the characters disposed on the portion of the tape situated between the printer and the projector will affect a minimum number of characters.

Specifically the invention still further contemplates the provision of an improved jump dissipating device embracing a bent or offset abutment and a finger for cooperating with such abutment to deflect the tape out of its path of movement between the printing mechanism and the projecting mechanism to form a loop and create sufficient friction to iron out or dissipate the vibrations transmitted to the tape by the ticker.

Specifically the invention still further contemplates an improved combination of ticker having a positive type wheel, a jump dissipating device, a screen, and projecting means, whereby a minimum number of characters on the tape will be located between the ticker and the projecting means.

The invention still further aims to provide an improved combination of a ticker, projecting means, jump dissipating device, tape drawing means, and rewind reel, whereby the rewind reel will be effectively arrested against actuation when the ticker is arrested.

These and other features, capabilities and advantages of the invention will appear from the subjoined detail description of specific embodiments of the invention illustrated in the accompanying drawings in which

Figure 1 is a fragmental end elevation of the improved combination;

Fig. 2 is a section on the line 2—2 of Fig. 1;
Fig. 3 is a fragmental enlarged plan of the jump dissipating device;

Fig. 4 is a fragmental enlarged end elevation of the jump dissipating device;

Fig. 5 is an enlarged side elevation of the tape drawing device and rewind mechanism;

Fig. 6 is a plan of the tape drawing device and rewind mechanism shown in Fig. 5;

Fig. 7 is a fragmental perspective of a positive type reel used with the combination illustrated in Figs. 1 and 2; and

Fig. 8 is a fragmental view illustrating the deflecting means used with a negative type reel.

In the embodiment illustrated there is provided a frame having a platform 1 on which is mounted the lamp housing 2 containing the lamp 3, and having a lens 4 for receiving the light rays from the lamp 3 and projecting it onto the deflector 5 preferably inclined as shown and mounted at the bottom of the extension 6, from which the light rays are projected upwardly to the lens 7 forming the light aperture for the extension 6 of the lamp housing.

To one side of the lamp housing there is formed a bracket 8 for supporting the ticker 9, which has a suitable printing mechanism including the type wheels 10 and a feeding mechanism including the feed roller 11. On the bracket 8, there is also formed an arm 12 for supporting the ticker tape supply reel 13, the tape T passing from the supply reel 13 under the feed roller 11 and type wheels 10 in the direction of the movement of discharge of the tape T from the ticker 9 across the light aperture to the upper surface of the lens 7, then over the guide rod 14 down to the tape drawing device including the driven roller 15 and idler 16, and from there under the finger 17 of the lever 18 to the rewind reel 19.

As shown in Fig. 2, the extension 6 is spaced a short distance from the guide 20 of the ticker just sufficient to permit the lug 21 to cooperate with the tape and press it into engagement with the curved abutment 22 preferably secured to the side of the extension 6. The lug 21 is secured to a rod 23 which extends through the weight bracket 24, which is pivoted to the arm 25, secured to the side of the extension 6. Between the weight bracket 24 and lug 21, the rod 23 is preferably provided with a weight 26 which is adjustably secured thereto. The rod 23 is also adjustably connected to the weight bracket 24 as shown in Fig. 4.

By special reference to Figs. 2, 3 and 4, it will be seen that the upper surface of the abutment 22 is curved downward from the upper surface of the lens 7, that is, at the edge of the light aperture formed by the lens 7, and that the lug 21 has a tail piece which is adapted to press the tape T into engagement with such curved surface of the abutment 22 and deflect it out of its path of

movement from the printing wheel to the lens 7 to form a loop and cause an extended area of the tape T to have both of its faces engaged, thereby creating an extended friction creating surface effectively to iron out any vibrations transmitted to the tape T by the ticker 9, that is, either by the type wheels 10 or feed roller 11.

When the type wheels 10 have positive characters formed thereon, as illustrated in Fig. 7, there can be used therewith an ordinary projecting lens mounted in the housing 21, which is supported by the bracket 28 extending from the upper end of the extension 6. With such lens, a single deflecting mirror 29 and screen 30 can be used. In the present instance, the mirror 29 is mounted in a housing 31 disposed at an angle to the screen 30, also mounted in said housing 31, which housing 31 is preferably supported in place by brackets such as the bracket 32 connected to a wall or other support. With this combination, the type characters will of course appear negative on the tape, and when so appearing and the printed surface is facing upwardly as illustrated in Figs. 1 and 2, the light rays will project images of such negative characters to the projecting lens in the housing 27 where they will be inverted and projected to the mirror 29, which mirror 29 will deflect the characters on said screen 30 in its legible reading order.

As shown in Figs. 5 and 6, a motor 33 is there provided having a shaft 34 provided with a sheave 35, which is connected to the sheave 36 by the belt 37. The sheave 36 is mounted on the shaft 38 having a worm 39 in mesh with the worm wheel 40 mounted on the shaft 41 in the housing 42, which housing 42 is mounted on the platform 43 disposed below the platform 1. The housing 42 has two bracket arms 44 and 45. The bracket arm 45 has a journal 46 to receive the shaft 47, on which the driven roller 15 is fixed. The shaft 47 is provided with a sheave 48 which is preferably connected to the sheave 49 on the shaft 41 by a belt such as a spring belt 50. The arm 44 is likewise provided with a journal 51 for the shaft 52, on which the reel 19 is fixed, which shaft 52 is provided with a sheave 53 which is connected to the sheave 54 on the shaft 41 by a slip belt such as a spring belt 55.

The arm 45 has pivotally connected thereto the bracket 56 to the upper end of which is pivotally connected the idler 16 which serves to impinge the tape T in contact with the driven roller 15. The bracket 56 is also provided with a rod 57 having adjustably mounted thereon a weight 58, whereby the pressure to be exercised by the idler 16 may be controlled.

The reel 19 is preferably provided with a brake drum 59. From the arm 44 extends the arm 60 to which is pivotally connected the brake shoe 61 adapted to cooperate with the brake drum 59. The brake shoe 61 has extending therefrom the arm 18.

From the foregoing it will be seen that the tape passes from the tape drawing roller 15 and idler 16 down below the finger 17 to the reel 19, and that when the ticker is arrested, the rewind reel will continue to wind up the tape until the slack formed in the tape between the roller 15 and the reel 19 has been sufficiently taken up to raise the finger 17 and therewith force the brake shoe 61 into engagement with the brake drum 59, whereupon the reel will be arrested and the spring belt 55 will slip relative to the sheave 53.

From the foregoing it will also be seen that by this arrangement, when the ticker operates, the driving roller 15 and reel 19, although both being operated from the same source of power, the roller 15 will exercise a uniform drawing action on the tape T while the reel 19 due to its spring belt will slip relative to the driven rate of the motor 33 to compensate for the increasing speed transmitted to the tape by the increasing diameter of the reel, thereby ensuring a uniform drawing action on the tape between the roller 15 and the finger 21.

From the foregoing it will also be seen that the extended friction creating surface afforded by the lug 21 will serve to interrupt the drawing action exercised by the drawing roller 15 so that such drawing action will not be directly transmitted back to the ticker, thereby serving to protect the delicate parts of the ticker from injury by such drawing action.

When an additional mirror or deflector is provided as illustrated in Fig. 8, substantially the same combination aforesaid may be used with a negative type wheel. With a negative type wheel an additional inversion is required which will be effected by introducing an additional mirror. In the embodiment illustrated in Fig. 8, there is provided a screen housing 62 having a mirror 63 for initially receiving the images from the lens in the lens housing 27, from which mirror 63 the images will be transmitted to the mirror 64 and from there to the screen 65.

It is obvious that various changes and modifications may be made to the details of construction without departing from the general spirit of the invention as set forth in the appended claims.

I claim:

1. In a stock quotation projection machine, the combination with a horizontally disposed light aperture, of a tape puller for pulling the tape along said light aperture, an extended convex friction creating surface curving downwardly from said light aperture at the anterior end thereof, and a finger having a concave tape engaging face for frictionally pressing the tape between the convex face of said friction creating surface and said finger.

2. In a stock quotation projection machine, the combination with a horizontally disposed light aperture, of a tape puller for pulling the tape along said light aperture, an extended friction creating surface inclining downwardly from said light aperture at the anterior end thereof, and a finger having a tape engaging face conforming to said friction creating surface for frictionally pressing the tape between the face of said friction creating surface and said finger.

3. In a stock quotation projection machine, the combination with a light aperture, of a tape puller for pulling the tape across said light aperture, an extended convex friction creating surface disposed at the anterior end of said light aperture, and a finger having a concave tape engaging face conforming to said friction creating surface for frictionally pressing the tape between the convex face of said friction creating surface and said finger.

4. In a stock quotation projection machine, the combination with a condensing lens having a substantially vertically extending optical axis, of a tape feeding mechanism for feeding the tape longitudinally across one face of said lens in a horizontally extending path of movement with the printed matter on the upper face and readable

- longitudinally of the tape, a vertically extending translucent screen disposed above said light aperture and facing forwardly of the machine, a pair of upper inclined deflectors disposed adjacent to said screen, a source of light below the level of said screen and to one side of the ticker, a lower deflector for receiving a horizontally extending beam of light from said source of light and deflecting it upwardly through said condensing lens 5 and tape to form an image impressed converging light beam, an objective lens unit above said tape for receiving the image impressed light beam to invert the same and diverge it onto one of said inclined upper deflectors, which latter deflector in turn deflects the image impressed light beam onto said other upper inclined deflector which latter upper deflector in turn deflects the image impressed light beam onto the rear face of said translucent screen. 10
- 15 5. In a stock quotation projecting machine, the combination with a condensing lens having a substantially vertically extending optical axis, of a tape feeding mechanism for feeding the tape longitudinally across one face of said lens in a horizontally extending path of movement with the printed matter on the upper face and readable longitudinally of the tape from one side of the machine, a vertically extending translucent screen disposed above said light aperture and facing the other side of the machine, a pair of upper inclined deflectors disposed adjacent to said screen, means including a source of light for directing a beam of light upwardly through said condensing lens and tape to form an image impressed converging light beam, and an objective lens unit above said tape 20 for receiving the image impressed light beam to invert the same and diverge it onto one of said inclined upper deflectors, which latter deflector in turn deflects the image impressed light beam onto said other upper inclined deflector which latter upper deflector in turn deflects the image impressed light beam onto the rear face of said translucent screen. 25
- 30 5. In a stock quotation projecting machine, the combination with a condensing lens having a substantially vertically extending optical axis, of a tape feeding mechanism for feeding the tape longitudinally across one face of said lens in a horizontally extending path of movement with the printed matter on the upper face and readable longitudinally of the tape, a vertically extending translucent screen disposed above said light aperture and facing forwardly of the machine, a pair of upper inclined deflectors disposed adjacent to said screen, means including a source of light for directing a beam of light upwardly through said condensing lens and tape to form an image impressed converging light beam, and an objective lens unit above said tape for receiving

the image impressed light beam to invert the same and diverge it onto one of said inclined upper deflectors, which latter deflector in turn deflects the image impressed light beam onto said other upper inclined deflector which latter upper deflector in turn deflects the image impressed light beam onto the rear face of said translucent screen. 5

6. In a stock quotation projecting machine, the combination with a condensing lens having a substantially vertically extending optical axis, of a tape feeding mechanism for feeding the tape longitudinally across one face of said lens in a horizontally extending path of movement with the printed matter on the upper face and readable 15 longitudinally of the tape from one side of the machine, a vertically extending translucent screen disposed above said light aperture and facing the other side of the machine, a pair of upper inclined deflectors disposed adjacent to said screen, means including a source of light for directing a beam of light upwardly through said condensing lens and tape to form an image impressed converging light beam, and an objective lens unit above said tape 20 for receiving the image impressed light beam to invert the same and diverge it onto one of said inclined upper deflectors, which latter deflector in turn deflects the image impressed light beam onto said other upper inclined deflector which latter upper deflector in turn deflects the image impressed light beam onto the rear face of said translucent screen. 25

JAMES W. DECKER.
